UNITED STATES PATENT OFFICE.

OSCAR J. OLM, OF MINNEAPOLIS, MINNESOTA, ASSIGNOR OF ONE-HALF TO GUSTAV MONASCH, OF MINNEAPOLIS, MINNESOTA.

DISK-FEEDING MACHINE.

1,114,177.

Specification of Letters Patent. Patented Oct. 20, 1914.

Application filed July 6, 1912. Serial No. 708,073.

To all whom it may concern:

Be it known that I, OSCAR J. OLM, of Minneapolis, Hennepin county, Minnesota, have invented certain new and useful Improvements in Disk-Feeding Machines, of which the following is a specification.

My invention relates to machines for fastening washer-like disks to the body or flap of an envelop or other article.

10 The object of my present invention is to provide improved means for feeding a reinforcing disk or section, preferably in tape form, to an eyelet upsetting anvil and pin, preparatory to securing the reinforcing section to the envelop or other article. Generally these reinforcing sections, placed on the inner face of the envelop body and the flap, are fed by hand to the machine and my invention contemplates a much more 15 rapid and effective delivery of the reinforcing sections to the surface to be reinforced.

A further object is to provide improved means for punching a hole in the flap to receive the disk and eyelet.

25 Other objects of the invention will appear from the following detailed description.

The invention consists generally in various constructions and combinations, all as hereinafter described and particularly 30 pointed out in the claims.

In the accompanying drawings forming part of this specification, Figure 1 is a side elevation of the upper portion of the machine embodying my invention, showing the envelop in position for attaching the inner and outer disks thereto, Fig. 2 is a similar view, showing the mechanism in the act of cutting off a disk from the strip or ribbon, Fig. 3 is a view, partially in section, showing the disk feeding mechanism and the means for forming the hole in the flap at any point therein, Fig. 4 is a plan view of the tape or ribbon carrier, Fig. 5 is a longitudinal sectional view of the same, Fig. 6 is a detail view of the tape feeding rolls, Fig. 7 is a detail view of the clutch mechanism for operating the rolls, Fig. 8 is a detail sectional view of the means for securing uniform movement of the rolls and a corresponding feed of the tape, Fig. 9 is a detail view showing the device for operating the lever which disengages the tape carrier from the punching pin or die, Fig. 10 is a

view of the envelop showing the disks or washers secured to the body portion thereof, and the hole punched in the flap, Fig. 11 illustrates the completed envelop with the string thereon for securing the flap in its closed position, Fig. 12 shows a modified construction.

In the drawing, 2 represents the frame of the machine having a bracket 3 thereon supporting a reciprocating plunger 4. 5 is a lever pivoted at 6 on said bracket and having an antifriction bearing on an arm 7 which engages the upper end of the plunger to depress it against the tension of the springs 8. A treadle bar 9 is pivotally connected with the lever 5 and extends downwardly to an operating treadle, not shown.

10 represents a horn, having an anvil 11 formed thereon provided with a perforating pin 12 located in the path of the plunger.

13 represents a device by means of which eyelets are fed to the plunger in the usual 75 way, but as this eyelet feeding mechanism forms no part of my present invention I do not illustrate or describe it in detail herein.

14 represents a tape carrier, pivoted preferably at 15 on the horn 10 and adapted to 80 receive and guide the tape 16 from a reel 17. The carrier preferably has a top or cover 18 provided with slots or openings 19 through which the tape is visible, and also has a hole 20 adapted to register with a corresponding 85 hole 21 in a die block 21' secured to the bottom of the carrier. The floor of the carrier preferably has an opening 22 therein and a feed roll 23 having a roughened surface is mounted beneath said opening and yieldingly held toward a corresponding roll 24 above said opening by means of a spring 25. These rolls operate to feed the tape through the carrier, the upper roll engaging the surface of the carrier through an opening in 90 the cover. The rolls are secured preferably on shafts 26 and 27, the shaft 27 extending outwardly beyond the carrier and provided with a clutch device composed of members 28 and 29, the former being secured to the 100 shaft 27 and provided with peripheral ratchet teeth which are engaged by dogs 30 on the member 29. The dogs 30 are held in engagement with the ratchet teeth by springs 30' and springs 31' and 31'' engage 105 respectively the ratchet teeth and a notch

32' in the periphery of the disk 29. These last named springs operate to prevent backward movement of the clutch members.

An operating arm 31 is secured preferably 5 on the clutch member 29 which is held in place by lock nuts 32. When this arm is oscillated, the clutch member 29 will be moved to set the clutch and revolve the shaft 27 and feed the tape. A gear 33 is mounted 10 on the shaft 27 and meshes with a gear 34 on a shaft 26 so that the lower feed roll will be revolved simultaneously with the upper one. The feed of the tape is made uniform by means of a disk 35 on the roll 24 and having 15 peripheral notches 36 therein to receive a tooth 37 on a pivoted arm 38 which is yieldingly held in engagement with the disk by a spring 39. The notches are preferably V-shaped, so that the tooth 37 will center it- 20 self automatically in its notch and insure a uniform feeding of the tape with each movement of the feeding mechanism.

The carrier is arranged to oscillate vertically on its pivots to punch holes in the 25 tape at regular intervals and I may effect this punching operation by the mechanism which I will now describe in detail.

40 is a link, pivotally connecting the arm 31 with the long arm of a bell crank 41 30 which is pivoted at 42 on the machine frame. The short arm of said bell crank has an anti-friction roller 43 mounted thereon in the path of a beveled shoulder 44 provided on a vertically sliding bar 45 which is pivotally connected at its upper end with a lever 5, (see Fig. 1) so that on the upstroke of the lever 5 the bar 45 will be raised to move the beveled shoulder 44 into engagement with the anti-friction roller 43 and rock the bell 35 crank 41 and the arm 31 to feed the tape. The upward movement of the carrier is against the tension of a spring 46. A pin 47 is mounted on the bracket 3 and is adapted to register with the hole 21 when the carrier 40 is raised and perforate the tape above the hole 21, a guide 48 operating to prevent lateral movement of the carrier during the punching operation. In its depressed position the carrier rests upon a pin 49 and a 45 catch 50 is preferably provided to engage the end of the carrier and lock it in its depressed position. A spring 51 is connected with the bell crank 41 and tends to retract the bell crank and the roll operating arm 55 connected therewith to the position shown in Fig. 2. The bar 45 is provided with an anti-friction roller 52 which engages the underside of the carrier and positively raises it to the limit of its upward movement 60 against the tension of the spring 46. (See Fig. 1).

The cover 18 at the receiving end of the carrier is preferably turned upwardly, as indicated in Fig. 5, to form an inclined bearing surface 53 and a bell crank 54 pivoted

on the bracket 3 has one arm adapted to bear on said surface and its other arm projecting into the path of a spring pressed hook 55 mounted on the longitudinal edge of the bar 45. A spring 56 normally holds the short arm of the bell crank 54 against a pin 57. The punching pin 47 sticks in the hole 21 after punching the hole in the tape sufficiently to resist the tension of the spring 46, but as the bell crank 54 is positively actuated by the upward movement of hook 55 and bears on the inclined surface 53, it will force the carrier downward and insure its disengagement from the punching pin.

The carrier is preferably provided near its pivoted end with a cutting edge 58 which is adapted to coöperate with a similar edge on the anvil 11 to sever the tape between the perforations therein, the severed section forming a disk or washer on the inner surface of the envelop, being held on the anvil and the pin 12 by suitable spring devices 59.

To perforate the body portion of the envelop, the flap is opened and the envelop placed on the horn of the machine, as indicated in Fig. 1, there being a washer or disk on the anvil beneath the wall of the envelop. The attendant will then place a perforated disk over the pin 12 and the operation of the plunger 4 will insert an eyelet point over the pin 12 and upset the ends of the eyelets to secure the disks to the paper, the outer disk forming a holding means for the cord while the disk on the underside of the envelop acts as a reinforcement to the paper, preventing the eyelet from being pulled through the paper.

On the underside of the hcrn I prefer to provide a plate 60 having a series of holes 61 therein adapted to receive a punching pin 62 which is fitted into any one of a series of holes 63 provided in a lever 64 pivoted at 65 on the machine frame. The lever 64 is normally held in the position shown in Fig. 3 by means of a spring 66 and one end of said lever is in the path of the lower end of the bar 45. The downward movement of the bar 45 will rock the lever 64 and move the pin 62 upwardly into one of the holes 61 in the plate 60. When the envelop is placed on the horn the flaps 68 will extend in under the plate 60 and the upward movement of the pin 62 will perforate this flap, the position of the perforations depending upon the adjustment of the pin in the lever 64, a sufficient number of holes being provided in said lever to allow the perforation at any suitable point in the flap and adapt the machine for perforating flaps of envelops of different sizes.

To insure the separation of the lever 64 from the envelop flap I prefer to provide guides 69 secured to the side of the machine and projecting outwardly upon each side of the lever 64. The envelop flap is inserted be-

tween these guides and the plate 60 and the guides prevent the flap from following the pin and lever when they are drawn to the position indicated in Fig. 3. After the perforation has been made in the flap and the disks secured to the body of the envelop, the operator will remove the envelop from the horn, turn it over and secure a re-inforcing disk to the inner face of the flap and 10 the outer disk or washer to the outer face of the flap in the same manner as the disks are secured to the body of the envelop. The string is then attached and the envelop is ready for use.

15 In Fig. 12 I have shown a modification which consists in providing a perforation 70 in the upper wall of the carrier, forming a die to receive a punch 71 mounted on the horn 10 and adapted to register with the hole 70 to perforate the tape as it is fed between the upper and lower walls of the carrier. This perforation will take place when the carrier is tilted and its pivoted end is lowered, so that the punch will contact with 25 the tape and at the same time the severing knife 59 will cut the tape between the perforations. This construction I may prefer to employ in the machine, as it is simple and easily applied and may be more accurate 30 than the punching device described with reference to the previous figures.

In the operation of the machine, the tape will be fed toward the upsetting anvil and pin by the mechanism which operates the plunger, but as the forward end of the tape approaches the pin it will be tilted to direct the pin into engagement with the perforation in the tape, the perforation having been previously formed by the tilting of the carrier. When the eyelet upsetting pin has engaged the hole in the tape the carrier will be tilted to bring the tape into engagement with the punch to perforate another hole, and at the same time the severing knife will 45 become effective to cut the tape between the perforations, and during the time that the tape is being severed and punched, the severed section will be held down on the anvil by the yielding means described until 50 the descent of the plunger secures it to the surface to be reinforced.

I do not wish to be confined in this application to the mechanism shown and described for operating the various parts of the machine, as obviously these features may be changed in many ways and still be within the scope of my invention.

I claim as my invention:

1. The combination, with a horn having an anvil and a pin thereon over which the material to be reinforced is placed, of means for feeding a reinforcing tape having a perforated end to said pin, means for lowering the perforated end of the tape to engage the pin and allow it to enter a perforation,

means for severing the tape in the rear of the perforation engaged by the pin, and means for inserting an eyelet through the material and the perforation in said reinforcing element.

70

2. The combination, with a horn having an anvil and pin thereon, of a tilting carrier, means for feeding a perforated tape through said carrier, means for tilting said carrier to lower the end of the tape to engage said pin and allow it to enter a perforation in said tape, means for severing the tape in the rear of the perforation engaged by the pin, and means for securing the severed section of the tape to material resting on said pin and anvil.

75

3. The combination, with a horn having an anvil and a pin thereon, of a pivoted carrier adapted to support a perforated tape, means for feeding said tape to said pin and anvil to engage said pin with a perforation therein, a stationary perforating pin, means for swinging said carrier to bring the tape therein into engagement with said perforating pin to perforate the tape, means for severing the tape in the rear of the perforation engaged by the pin, and means for securing the severed section to material to be reinforced.

85

4. The combination, with a horn having an anvil and a pin thereon, of a pivoted carrier having a severing knife at one end, means for feeding a perforated tape through said carrier to engage said pin with a perforation therein, means for perforating the tape at regular intervals, means for tilting said carrier to perforate the tape and sever it in the rear of the perforation engaged by the pin, and means for securing the severed section to the surface of material on said horn.

95

5. The combination, with a horn having an anvil and a pin thereon, of a carrier pivoted near one end and having a severing knife near said end, means for feeding a perforated tape through said carrier to engage said pin with a perforation therein, a punch arranged in the path of said carrier to punch the paper during the tilting movement of said carrier, said knife operating to sever the tape in the rear of the perforation engaged by the pin during said tilting movement, and a plunger co-operating with said pin to set an eyelet to secure the severed tape section to material on said horn.

110

6. The combination, with a reciprocating plunger and means for feeding eyelets thereto, of a horn having an anvil and pin beneath said plunger, a pivoted carrier adapted to receive a tape and means for feeding the tape therein to said pin and anvil, a punch and die located near the pivot of said carrier and operating during the tilting movement of said carrier to punch the tape, means for tilting said carrier, to engage said

115

120

125

130

pin with a perforation in the tape, and means for severing the tape in the rear of the perforation engaged by the pin.

7. The combination, with a horn having an anvil and a pin thereon, of a carrier pivoted near one end and having a severing knife at that end, means for feeding a tape through said carrier, means for tilting said carrier, a punch and die provided in connection with said carrier between said pivot and severing knife and operating to perforate the tape through said carrier, said knife operating to sever the tape in the rear of the end perforation during the tilting movement of said carrier, and means for securing the severed section to the surface of material on said horn.

8. The combination, with a reciprocating plunger and means for feeding eyelets thereto, of a horn having an anvil and pin beneath said plunger, a carrier adapted to receive a tape and means for feeding it therein to said pin and anvil to have the pin engage a perforation in the tape, means for perforating the tape at regular intervals, means for lowering the end of the tape to engage said pin and allow it to enter the perforation in the tape, and means for severing the tape in the rear of the perforation engaged by the pin, the descent of the plunger forcing the eyelet through the material and the perforation in the severed section, for the purpose specified.

9. The combination, with a horn having an anvil and pin thereon over which the material to be re-inforced is placed, of means for perforating a tape, means for feeding it to engage said pin with a perforation, means for severing the tape in the rear of the perforation engaged by the pin, a spring arranged to hold the severed tape section upon said pin and anvil with a yielding pressure, and means for inserting an eyelet through the material and the perforation in said tape section.

10. The combination, with a reciprocating plunger and means for operating the same, and means for feeding eyelets into the path of the plunger, of an eyelet upsetting anvil and pin in line with said plunger, and mechanism actuated by said plunger operating means for perforating and feeding a tape to engage said pin with a perforation in the tape, and means for severing the tape in the rear of the perforation engaged by the pin.

11. The combination, with a horn having an anvil and pin thereon over which the material to be re-inforced is placed, of a pivoted carrier having means for feeding a perforated tape to said pin, the discharge end of said carrier being normally above the level of said pin, means for tilting said carrier to lower the tape upon said pin, means for severing the tape in the rear of the perforation engaged by the pin, means

for yieldingly holding the severed section on said anvil, and means for inserting an eyelet through the material and the perforation in said severed section.

12. The combination, with a horn having an anvil and pin thereon over which the material to be re-inforced is placed, of a pivoted carrier adapted to receive a tape and having means for feeding the tape toward said pin, a perforating pin in the path of said carrier and adapted to punch the tape at uniform intervals, means for tilting the carrier to lower the forward end of the tape to engage said anvil pin, said carrier having means for severing the tape in the rear of the perforation engaged by the pin during the tilting movement of the carrier, and means for inserting an eyelet through the material and the perforation in the severed section of said tape.

13. The combination, with a horn having an anvil and pin thereon over which the material to be re-inforced is placed, of a tilting carrier having means for feeding perforated tape portions to said pin, the discharge end of said carrier being normally above the level of said pin to allow said pin to enter the perforation in the forward tape portion during the feeding operation, and means for inserting an eyelet through the material and the perforation in said forward tape portion.

14. The combination, with a horn having an anvil and pin thereon over which the material to be re-inforced is placed, of a tilting carrier having means for feeding a tape therein toward said pin, the discharge end of said carrier being normally in position to direct the forward portion of the tape over said pin, means for tilting said carrier to lower the forward portion of the tape on said anvil, and means for simultaneously perforating a succeeding portion of the tape.

15. The combination, with a horn having an anvil and pin thereon adapted to receive the body of an envelop placed thereon, of a plate mounted on the underside of said horn and having a series of perforations therein and against which the flap of the envelop rests when the body portion is placed on said horn, a lever having a series of holes therein and a pin adapted to fit said holes and enter a perforation in said plate to perforate the flap thereon, and means for actuating said lever.

16. The combination, with an eyelet upsetting anvil and pin, of means for perforating a tape, means for feeding the tape and tilting it to engage the pin with a perforation therein, means for holding the tape on said pin, and means for severing the tape in the rear of the perforation engaged by the pin.

17. The combination, with an eyelet up-

70

130

- setting anvil and pin, of means for feeding a tape having a perforation in its forward portion to engage said pin with the perforation in the forward portion, and means 5 for simultaneously severing the tape in the rear of said forward portion and perforating the adjacent portion.
18. The combination, with a reciprocating plunger, and means for operating the same 10 and means for feeding eyelets into the path of said plunger, of an eyelet upsetting anvil having a pin in line with said plunger, a tilting carrier adapted to deliver a perforated tape section to said pin to engage 15 said pin with the perforation therein, and having means for perforating the tape and means for severing it in the rear of the perforation engaged by the pin, and means actuated by the movement of said plunger operating means for successively feeding the 20 tape to said pin and tilting said carrier to sever the tape in the rear of the perforation engaged by the pin.
19. The combination, with a reciprocating plunger and means for operating the same, and means for feeding eyelets into the path of the plunger, of an eyelet upsetting anvil and pin in line with said plunger, means for perforating and feeding a tape 25 to engage said pin with a perforation in the tape, and means for severing a section of the tape containing said perforation.
20. The combination, with an eyelet upsetting anvil and pin, of means for perforating a tape, means for feeding the tape and engaging the pin with a perforation therein, means for holding the tape on said pin, and means for severing a section of the tape 30 containing said perforation.
21. The combination, with an eyelet upsetting anvil and pin, of means for feeding a 35
- tape having a perforation in its forward portion to engage said pin with said perforation, means for severing the tape in the rear of said forward portion, and means for 40 perforating the adjacent portion of the tape.
22. The combination, with an eyelet upsetting anvil and pin, of means for feeding a tape having a perforation in its forward portion to engage said pin with said perforation, and means for severing the tape in the rear of said forward portion. 45
23. The combination, with an eyelet upsetting anvil and pin, and means for feeding a perforated re-inforcing strip and for 50 causing engagement of the pin with a perforation in such strip, of a reciprocating plunger, means for feeding an eyelet into the path of said plunger, and means for operating said plunger and thereby passing the 55 eyelet through the perforation in said strip and upsetting the eyelet.
24. A machine of the class described having, in combination, coöperating setting dies, a holder for washers in strip form, 60 means for feeding the strip to position the endmost washer in alinement with the dies, and means for severing said washer from the strip after it has been so positioned.
25. A machine of the class described having, in combination, coöperating setting dies, means for feeding a strip of washers to 65 position the endmost washer in alinement with the dies, and means for severing said washer from the strip after it has been so positioned.
- In witness whereof, I have hereunto set my hand this 1st day of July 1912.
